L. J. BLACK.
HYDRAULIC SWIVEL.
APPLICATION FILED APR. 8, 1921.

1,408,975.

Patented Mar. 7, 1922.

UNITED STATES PATENT OFFICE.

LEE J. BLACK, OF BEAUMONT, TEXAS.

HYDRAULIC SWIVEL.

1,408,975.

Specification of Letters Patent.

Patented Mar. 7, 1922.

Application filed April 8, 1921. Serial No. 459,684.

To all whom it may concern:

Be it known that I, LEE J. BLACK, a citizen of the United States, residing at Beaumont, in the county of Jefferson and State of Texas, have invented certain new and useful Improvements in Hydraulic Swivels, of which the following is a specification.

This invention relates to hydraulic swivels used with rotary well drilling machines for 10 making a water-supply connection with the drill stem.

The present device is an improvement over the one disclosed in Patent No. 1,372,- 266, issued March 22, 1921, and the object 15 is to simplify the structure, and also to render the device more efficient and reliable in operation.

With the object stated in view, the invention consists in a novel combination and 20 arrangement of parts to be hereinafter described and claimed, and in order that the same may be better understood, reference is had to the accompanying drawing forming a 25 part of this specification.

In the drawing,

Figure 1 is an elevation of the device, partly in section; Figs. 2 and 3 are elevations slightly enlarged, of a water-head as viewed from different sides, and Fig. 4 is 30 a plan view of the water-head.

Referring specifically to the drawing, 5 denotes a swivel stem which passes through and is supported by the swivel cross-head 6, which latter is carried, as usual, by a bail 35 7 to which the draw-cable (not shown) is connected.

In the cross-head 6 is a cavity 8, the same extending downwardly thereinto from the top, and containing the bearing collar 9 and 40 other parts disclosed in the Patent No. 1,372,266 hereinbefore referred to, said collar having a screw-threaded connection with the swivel stem 5 and being locked on the latter by a lock nut 10.

45 The upper portion of the cavity 8 is screw-threaded to seat the base ring 11 of a water-head, the body 12 of the latter being integrally connected to the base ring by diametrically opposite webs 13. The base ring is 50 exteriorly threaded so that it may be screwed into the upper end of the cavity 8, and in this manner the water-head is rigidly, but detachably connected to the cross-head 6, and is formed below its body portion 55 with an open portion.

The upper end of the swivel stem 5 passes

through the ring 11 and it is connected to the body 12 to open thereinto. The swivel stem is, of course tubular, and as its upper end, which extends into the body 12, is open, 60 the water discharged into the latter is permitted to flow into the swivel stem. To the top of the body 12 is connected a goose-neck 14 to which the water supply hose is connected, a fragment of the latter being shown 65 at 14a.

A stuffing box is provided in order to prevent leakage of water from the body 12 where the swivel stem 5 enters the same. This stuffing box is shown at 15, it being 70 screwed into an opening in the bottom of the body 12. The stem 5 passes through the stuffing box 15, and the latter is provided with a screw cap 16 for holding a gland or follower 17, a packing 18, and a brass ring 19, the latter being located at the inner end of the stuffing box.

In order to prevent leakage of oil from the cavity 8 where the stem 5 passes through the base ring 11 of the water-head 12, said 80 ring is also fitted with a stuffing box 20 through which the stem passes, said stuffing box being also provided with a screw cap, packing, etc., the same as the stuffing box 15. The webs 13 joining the ring 11 and body 12 85 leave the stuffing boxes 15 and 20 exposed so that they are readily accessible for re-packing, tightening of the screw caps, etc.

The direct connection of the water head 12 with the cross-head 6 renders unnecessary 90 the anti-friction bearings employed in connection with the water-head disclosed in Patent No. 1,372,266 hereinbefore referred to. The cross head 6 usually stands still and as it carries the water head 12, the latter is also stationary. The stem 5 revolves 95 inside the stuffing boxes 15 and 20, and as the latter are held centered with respect to the bearing in the cross-head which supports the stem, there is no side thrust to take care 100 of.

I claim:

1. In a hydraulic swivel, a swivel stem, a cross-head through which the swivel stem passes, and from the top of which said stem 105 projects, said cross-head having a cavity opening through the top thereof, bearings in said cavity for the swivel stem, a water head having a base ring and webs integrally connecting said head and ring, the base ring 110 being secured in the aforesaid cavity of the cross-head, the swivel stem passing through

the base ring and into the water-head, and the latter having a supply connection and an outlet into the stem, and stuffing boxes for the swivel stem carried by the water-head and the base ring.

2. In a hydraulic swivel, a swivel stem, a cross-head supporting the swivel stem and from the top of which said stem projects, a water-head comprising a body portion, a base ring and spaced webs integrally connecting said body portion and base ring, means for connecting the base ring to the cross-head, the swivel stem passing through the base ring and into the body portion of the water-head, the latter having a supply connection and an outlet into the stem, and stuffing boxes for the swivel stem carried by the base ring and the body portion of the water-head, said stuffing boxes being exposed 15 for access through the spaces between the aforesaid webs.

3. In a hydraulic swivel, a swivel stem, a cross-head supporting the swivel stem and from the top of which said stem projects, a water-head comprising a body portion, a base ring and spaced webs integrally connecting said body portion and base ring, means for connecting the base ring to the cross-head, the swivel stem passing through the base ring and into the body portion of the water-head, the latter having a supply connection and an outlet into the stem, and

a stuffing box for the swivel stem carried by the body portion of the water-head, said stuffing box being exposed for access through 35 the spaces between the aforesaid webs.

4. In a hydraulic swivel, a swivel stem, a cross-head supporting the swivel stem and from the top of which said stem projects, a water-head comprising a body portion and an open portion which is connected to the cross-head, the swivel stem passing through said open portion and into the body portion, the latter having a supply connection and an outlet into the stem, and a stuffing box 40 for the swivel stem carried by the body portion of the water-head, and exposed for access through the open portion of the water-head.

5. In a hydraulic swivel, a swivel stem, a cross-head supporting the swivel stem and from the top of which said stem projects, a water-head comprising a body portion and an open portion which is connected to the cross-head, the swivel stem passing through 55 said open portion and into the body portion, the latter having a supply connection and an outlet into the stem, stuffing boxes for the swivel stem on the open portion and the body portion of the water-head, and exposed 60 for access through said open portion.

In testimony whereof I affix my signature.

LEE J. BLACK.
